(57) **CLAIM**

We claim the ornamental design for a combined bottle and bottle closure, as shown and described.

DESCRIPTION

FIG. 1 is a top perspective view of a combined bottle and bottle closure showing our new design;

FIG. 2 is a top view of the combined bottle and bottle closure shown in FIG. 1.

FIG. 3 is a bottom view of the combined bottle and bottle closure shown in FIG. 1.

FIG. 4 is a side view of the combined bottle and bottle closure shown in FIG. 1, wherein the opposite side is a substantial mirror image of this side, except for the markings on the bottle.

FIG. 5 is another side view of the combined bottle and bottle closure shown in FIG. 1, wherein the opposite side is a substantial mirror image of this side, except for the markings on the bottle.

FIG. 6 is an enlarged side view of the bottle closure shown separately for clarity of disclosure, wherein all other side views are substantially a mirror image of this side; and,

FIG. 7 is a bottom perspective view of the bottle closure shown in FIG. 6.

The present application is directed to the shape and contour of a bottle and closure for the bottle, such as a pressurized bottle for dispensing cleaning liquids of the design illustrated in the drawings. Features of the drawings shown in broken lines are not considered part of the design currently sought to be patented.
